UNITED STATES PATENT OFFICE.

JOHN O. BECVAR, OF BROOKFIELD, ILLINOIS.

SASH FASTENER.

Application filed January 19, 1925. Serial No. 3,262.

To all whom it may concern:

Be it known that I, JOHN O. BECVAR, a citizen of the United States, and a resident of Brookfield, county of Cook, and State of Illinois, have invented certain new and useful Improvements in Sash Fasteners, of which the following is a specification.

My invention relates to sash fasteners and has for an object to provide an improved device for fastening the sashes of a window together so as to prevent opening thereof either from their closed position or when opened to any desired extent. Another object is to provide means which will permit closing the windows but which will automatically operate to prevent opening thereof.

Other objects will appear hereinafter.

The invention consists in the combinations and arrangements hereinafter described and claimed.

The invention will be best understood by reference to the accompanying drawings, forming a part of this specification, and in which,

Fig. 1 is a front elevation of a window with my invention applied thereto;

Fig. 2 is a vertical cross section of a window, with my invention shown in side view thereon;

Fig. 3 is an enlarged side view of the invention with the eccentric member secured in its inoperative position;

Fig. 4 is a detail section taken on line 35 4—4 of Fig. 3;

Fig. 5 is a front elevation of a window with a modified form of my invention mounted thereon;

Fig. 6 is a vertical cross section of a window showing said modified form in side elevation;

Fig. 7 is an enlarged vertical cross section of the invention; and

Figs. 8 and 9 are detail sectional views taken respectively on lines 8—8 and 9—9 of Fig. 7.

My improved sash fastener comprises a suitable bracket 10 adapted to be fastened to one of the window sashes 11, and is preferably arranged to be secured to the top of one of the stiles 12 of the lower window sash, near the adjoining stile 13 of the upper sash, as shown, and preferably by the use of a lug 14 extending downwardly from the bracket, and openings 15 provided in said lug and in the bottom of the bracket for

receiving screws 16 which extend through the openings into the stile. These fasteners are preferably provided in pairs, to have one mounted on the top of each of the stiles 60 of the lower sash.

The automatic fastening means comprises an eccentric or member 17 which is secured on a pivot pin 18 extending transversely of the bracket, to permit outward swinging 65 of the eccentric. A strip of covering means 19 of rubber or suitable friction material is mounted on the peripheral surface of the eccentric by means of lugs 20 cut and struck up from the peripheral surface and 70 then bent inward onto the rubber strip 19, as shown. A spring 21 is coiled on pin 18 and has one end fastened on a member or arm 22 secured to the pin, and has its other end 23 fastened to an arm or member 24 seated 75 on a pin 25 which is slidably mounted in eccentric 17. A spring 26 on pin 25 bears against arm 24 to constantly urge said pin into an opening 27 provided on the upper, outwardly curved end 28 of bracket 10, 80 thereby fastening or locking the eccentric in its inoperative or release position, as shown in Figs. 3 and 4.

Means is provided for conveniently releasing the locking pin 25, in order to permit spring 21 to move the eccentric into locking engagement with the adjacent sash, as shown in full lines in Fig. 2. This means preferably includes a hammer or member 29 which is mounted with a pin 30 upon an 90 outwardly curled lip 31 on bracket 10, and a finger 32 is provided on said hammer to prevent excessive release movement of the hammer. A knob 33 on the inner side of the hammer engages the outer end of pin 95 25 to press it inwardly for releasing the portion 28 on the bracket to permit operative movement of the eccentric, and a thumb plate 34 is provided on the hammer for conveniently depressing the same. A 100 finger lug 35 may also be provided at the outer end of eccentric 17 for conveniently returning the eccentric to its inoperative position.

In the modified form shown in Figs. 5 105 to 9 inclusive the essential elements of the construction are the same as in the preceding form disclosed in Figs. 1 to 4 inclusive, but the bracket 10' is provided with a slanting or inclined bottom portion 10'' to be adapted for mounting on the slanting upper face of a style 12', instead of on the hori-

zontal upper face of a style 12 as shown in the preceding form. In this modified form the elements have been indicated by the same numbers as in the preceding form and with the addition of the prime mark, and the individual enumeration of the elements is therefore deemed unnecessary.

In use the latch is mounted on the top of one of the stiles, but preferably on both 10 stiles, of the lower sash, and when the locking pin 25 is released by depressing hammer 29, the eccentric is automatically pressed against the adjoining stile of the upper sash, by spring 21. These sashes are then 15 locked against any further overlapping or opening of the window, but will at the same time permit closing of the window, and the sashes may thus be fastened together when 20 opened to any desired extent, and will also be automatically locked in the closed position.

While I have illustrated and described the preferred form of construction for carrying my invention into effect, this is capable of 25 variation and modification without departing from the spirit of the invention. I, therefore, do not wish to be limited to the precise details of construction set forth, but desire to avail myself of such variations and 30 modifications as come within the scope of the appended claims.

Having described my invention, what I claim as new and desire to secure by Letters Patent is:

35 1. A sash fastener comprising a bracket

member arranged for mounting it on the stile of one window sash, an eccentric case pivoted in said bracket and having a frictional covering strip thereon for engaging the adjoining stile of the other sash, lugs 40 struck up from said eccentric and bent over to hold said strip in position, resilient means to press said eccentric into engagement with said other stile, and means on said eccentric to engage said bracket and hold the 45 eccentric in its inoperative position.

2. A sash fastener comprising a bracket with means for mounting it on the top of a stile of the lower window sash, an eccentric casing mounted with a pivot member in said 50 bracket and provided with a friction surface adapted to swing outwardly into engagement with the adjoining stile of the upper window sash, a pin slidably mounted in said eccentric, spring means in said casing on said pin to slide it into engagement with said bracket and hold the eccentric in its inoperative position, a spring in said 55 casing coiled on said pivot member and having one end fastened thereon and the other end fastened on means on said slidably pin for automatically moving and holding said eccentric in engagement with said adjoining stile, and finger engaged means bent up from said eccentric for conveniently returning it to its inoperative position.

In testimony whereof I have signed my name to this specification.

JOHN O. BECVAR.
